COMBINED AIR CONDITIONING AND
HEATING UNIT

William W. Hallinan, Mendota, Ill.

Application July 22, 1940, Serial No. 346,763

16 Claims. (Cl. 236—9)

The present invention relates to combined air conditioning units, and is particularly concerned with heating units of the coal stoker type, including arrangements for effecting a filtering and circulation of the heated air, and for maintaining the air of one or more rooms at a predetermined temperature with a maximum efficiency.

One of the objects of the present invention is the provision of an improved heating and air conditioning unit of the stoker type in which the blowers for circulating air and for providing the air for combustion are all driven from the same motor and in which the stoker and furnace are all embodied in one housing so that they are adapted to be installed as a unit.

Another object of the invention is the provision of an improved heating and air conditioning unit of the stoker type in which the hopper for the stoker is located inside the housing and subjected to cooling by the circulation of cold air about the hopper so that there is no hazard due to the possibility of ignition of fuel in the hopper and no possibility of the escape of smoke from the hopper into the furnace room or air circulation channels.

Another object of the invention is the provision of an improved air conditioning and heating unit of the stoker type, which is capable of economical manufacture, and which is sturdy and adapted to be easily cleaned, and in which all of the moving mechanism is readily available for inspection or repair.

Another object is the provision of an improved stoker controlling system which is adapted to eliminate the use of deep fuel beds and to regulate the coal feed and the air according to the steam pressure or bonnet temperature.

Another object of the invention is the provision of an automatic stoker fired air conditioning unit of modern design so constructed as to include all of the elements of winter air conditioning in one unit and so as to conserve the basement floor space.

Another object of the invention is the production of a complete winter air conditioning unit which is coal fired and which utilizes but one electric motor to furnish air for the combustion of the coal and air for the circulation of air through the conditioning unit and space to be heated by it.

Another object of the invention is the provision of an improved automatic coal fired air conditioning unit which has a heating efficiency

higher than that ever before attained by the devices of the prior art.

Another object of the invention is the provision of an improved air conditioning and heating unit and controlling system which is adapted to eliminate the room temperature overrun above the thermostat setting that is commonly present in the stoker fired units of the prior art, thus conserving fuel and raising the overall efficiency of the heating unit to a maximum.

Another object of the invention is the provision of an improved heating system which is adapted to operate at a high rate of fuel and air feed when the bonnet temperature or steam pressure is below a predetermined value and which is also adapted, as soon as the steam pressure or bonnet temperature reaches such value, to change the fuel feed and air supply in such manner that air will continue to be supplied to burn up the excess fuel that has been forced into the fire pot on high feed, thus maintaining efficient combustion without excessive coal feed until the fuel previously supplied has been burned up and the fire bed is reduced to a minimum depth, unless the steam pressure or bonnet temperature drops below the predetermined minimum again, in which case the stoker is fired at high coal and air feed.

Another object of the invention is the provision of an improved air conditioning and heating unit and controlling system for it, by means of which the fuel feed may be cut off before the room thermostat is satisfied and the furnace operated at reduced air supply, in order to consume all of the fuel previously forced into the burner, thus reducing the fuel bed depth to a minimum at the time or just about the time when the thermostat will be satisfied for the purpose of eliminating the regular room temperature over-run above the thermostat setting.

The solid fuel burners of the prior art with which I am familiar operate with either a full fuel feed or a full air feed, or a combination of both, until the room thermostat is satisfied, thus causing an over-run of the thermostat setting and a stopping of the burner by the thermostat when there is a large fuel bed in the furnace.

This large fuel bed produces smoke and wastes the fuel at this time because the combustion air is also shut off in the devices of the prior art, when the fuel feed is stopped.

Another object of the invention is to provide an improved air conditioning and heating unit in which the same motor operates the air circu-

lating blowers for the space to be heated, and the blower for the air of combustion, and in which the supply of air for combustion is not completely shut off, but is merely reduced so that when the motor is operating the fuel bed in the furnace is still provided with a reduced supply of air to reduce smoking and produce a more perfect combustion.

Another object of the invention is to produce a complete winter air conditioning unit in which the entire motor power assembly, consisting of the air conditioning blowers, burner blower, motor, and fuel feed gear casing, is easily removable and adapted to be replaced as one unit.

Another object of the invention is the provision of an air conditioning and heating unit for winter operation in which a solid fuel burner, a fuel storage hopper, a furnace, an air conditioning blower, the air filters, controls, wiring, and humidifier are all included in one unit, fully assembled and tested in such manner that the unit may be shipped from the factory in condition to be installed in the furnace room and merely connected with the chimney and electric light power supply for immediate operation.

Other objects and advantages of the invention will be apparent from the following description and the accompanying drawings, in which similar characters of reference indicate similar parts throughout the several views.

Referring to the five sheets of drawings,

Fig. 1 is a view in perspective of the air conditioning and heating unit embodying the invention, with certain covers removed, to show the details of construction;

Fig. 2 is a vertical sectional view, taken on the plane of the line 2—2 of Fig. 1, showing further details of construction of the housing and mechanism;

Fig. 3 is a front elevational view, partially broken away, and with a cover removed, to show the details of the operating mechanism and course of circulation of the air;

Fig. 4 is a rear elevational view of the unit;

Fig. 5 is a front elevational view of the unit;

Fig. 6 is a fragmentary sectional view, showing the details of construction of the front wall;

Fig. 7 is a fragmentary sectional view, taken on a plane passing through the axis of the blowers, and showing the motor and other operating mechanism in elevation in a modification where the blowers are located on the high speed shaft of the gear box;

Fig. 8 is a similar view of another modification where the blowers are arranged on the motor shaft;

Fig. 9 is a wiring diagram showing the circuits and apparatus for control of the heating system embodied in the present unit.

Fig. 10 is a top plan view of the furnace housing, showing the air chambers surrounding the parts of the furnace.

Referring to Figs. 1 and 2, the present air conditioning and heating unit is preferably enclosed in a sheet metal housing which is substantially rectangular in plan and side and end elevation.

This housing preferably includes a bottom plate 20 of sheet metal which is adapted to support all of the rest of the unit. The bottom plate 20 is preferably substantially rectangular in shape, and is provided about its borders with an upwardly extending flange 21 at its front end, which carries the horizontally extending flange 22.

The horizontally extending flange 22 has an upwardly extending attachment flange 23 extending across the rear end and the two sides of the housing, while the front end of the housing 5 may be provided with a box-like frame member 24, forming a transverse frame member and sill for an opening leading to the operating mechanism.

The outer housing of the unit preferably includes the side panel members 25, 26 and the end panel members 27, 28 (Figs. 3-5). The side panel members 25, 26 may be identical in shape, and they comprise sheet metal members provided with the straight lower border 21, and at the 15 lower edge the side panels 25, 26 may be secured in overlapping relation to the upwardly extending flange 23 preferably by means of screws or a Pittsburg seam or clamp.

Each side panel is preferably provided at each 20 of its vertical ends with a pair of flanges 29, 30, one at the front, and one at the rear, these vertical flanges being at substantially right angles to the main body of each panel 25, 26, and the bend between the flanges being partially cylindrical, or what may be described as an easy bend, giving the exterior of the housing rounded corners.

The base flanges 22 are correspondingly curved, and the attaching flanges 23 correspondingly curved to fit the side panels 25, 26 at the bottom with their vertical flanges 29 and 30.

The top of the housing is preferably provided with an upper frame member 31, comprising a substantially rectangular frame of sufficient size to fit inside the side panels 25, 26 at the top. 35 This frame has four sides, and may be made of one integral piece, or a number of pieces bolted together, and each side of the frame comprises a vertically extending flange 32 adapted to fit 40 inside the side panels 25, 26 and offset 33, and a partially cylindrical curved portion 34, which terminates with its edge 35 extending in a substantially horizontal plane. The rear part of the rectangular frame 31 may be of similar construction, having its lower flange 32 engaged inside the rear end panel 27.

The rear end panel 27 may also overlap the vertically extending flanges 30 of the two side panels, to which they may be secured by welding, 50 riveting or other convenient fastening means, welding over the full length being preferred.

The rear end panel 27 is preferably provided with a pair of clean-out openings which are closed with the covers 36, 37, and with another 55 opening for access to the fire pot, which is closed by the cover member 35. At its front end the top frame 31 has a depending flange without the offset 33, the inside of the flange being engaged by the front panel 28.

This front panel comprises a rectangular piece of sheet metal which has its lower edge provided with a horizontally extending flange 38 and a downwardly extending flange 39, which engage the top and inside of the box-like sill 24.

The curved flanges 29 of the side panels are 60 preferably provided with offsets and flanges 40 extending laterally under the end panel 28, when it is in the position of Fig. 5. The end panel 28 is held in place on one side by the flanges 40 behind it, and on the other side by the flange 39 extending down below the sill 24, and the depending flange 32 of the upper frame 31, which is outside the end panel 28. The end panel 28 70 may be removed by lifting it until the flange 39 clears the sill 24 so that the lower end may be

moved outward and downward to cause the upper edge of the end panel 28 to clear the depending flange 32.

This panel also is preferably provided with an opening which may be closed by means of a hinged closure 41. This opening is utilized for access to the hopper. The actual opening 42 to the hopper is preferably trapezoidal in form, for a reason further to be described.

At its upper end the main housing is closed by the upper frame 31, which has a horizontal body portion 43, effecting a substantial closure, except for the openings 44, 45, and 46. The opening 46 is utilized for passage of the smoke pipe 47, which extends to the chimney.

Openings 44 and 45 are each preferably provided with angular frames which are rectangular in plan and which serve for connecting the cold air ducts and hot air ducts. Each of these frames is preferably provided with a vertical flange 48 and a horizontal flange 49. In each case the horizontal flange is secured to the lower side of the body 43 of the top frame or panel, and the vertical flange 48 passed through the aperture 44 or 45.

All of the exterior panels or side portions of the housing, including the top and bottom, may be heat insulated with one or more inner layers of heat reflecting paper, corrugated asbestos cardboard, and asbestos blankets, or any one or more forms of such insulation.

The rectangular air ducts leading from the rooms may be attached to the flanges 48 and may have their lower edges resting on the top panel 43 of the housing. The opening 44 is utilized for a cold air duct, and the opening 45 for the hot air duct.

The fire box housing, indicated by the numeral 50, preferably rests upon a plurality of legs 51, one located at each corner of the base 52. These legs may consist of insulating bricks or firebrick secured in place by through bolts or other convenient fastening means. The fire box 50 has a substantially rectangular base 52 and side panels 53, which are rectangular in shape.

These side panels are joined at the rear end to a vertical end panel 54, and at the other end to a front panel 54', which may be considered as being composed of a rectangular part and an integral trapezoidal portion.

The trapezoidal portion of this panel is used to cause the furnace housing 50 to taper toward the top. A pair of sloping roof panels 55 are used, one on each side for covering the tapered portion of the furnace housing 50, and another sloping panel 56 is used on the rear side and provided with an aperture 57 leading to a rectangular box-like conduit 58, which is closed by the door 35.

At its upper end (Fig. 10) the furnace is formed with a box-like portion 59, which may be closed by a rectangular top plate that is provided with a U-shaped slot 59', defining an air circulation conduit inside the outer portion of the box 59 and surrounding the inner portion 60 of the furnace top. This box-like portion of the furnace has a lower side plate 63 of the same shape as the top plate shown in Fig. 10, except that there is an aperture 64 for receiving the upwardly extending part of the main furnace housing 50. This part has an upwardly extending frame member 65 on each side which prevents direct communication between the chamber 66 and the chamber 67 through the aperture 68, which is connected to the chimney 47.

It will be noted that there are air channels extending from the air conditioning blowers through and between the furnace and upper radiator box and surrounding the chimney.

5 The box-like portion 60 is wider than the upper extension 59 of the furnace housing, and the side plates 69 of the upper extension 59 of main furnace housing 60 serve as baffles. The upper extension 59 of the main furnace housing 60 has an aperture at 70 on its rear side above the rear plate 54, so that the gases may pass upward in the housing 50 into the extension 59 through the aperture 70, where they are split in two directions, passing outside of the side plates 69 and inside of the side plates 71 to the chamber 67, which is in communication with the chimney 47.

10 The clean-out openings previously described as being closed by the doors 36 and 37 are in connection with the passages 72 on both sides of the main furnace housing extension 59 inside the plates 71. These apertures are connected with the furnace housing by rectangular conduits 73 terminating in the doors 36, 37.

15 23 In addition to being supported on the legs 51, which are preferably secured to the bottom plate 20 of the heating unit, the furnace housing is tied to the rear end wall by the clean-out door conduits 58 and 73 and to the top of the unit 20 housing by the chimney 47.

25 It will thus be observed that the furnace housing is spaced from the unit housing on all sides so that the heated walls of the furnace housing may come in direct contact with air inside the heat unit housing for radiation and conduction of heat to the air.

30 33 The unit housing is preferably provided with a depending baffle 74 extending from its top panel 43 between the cold air opening 44 and the hot air opening 45. This panel 74 fits the inner walls of the side panels 25 and 26, and is firmly secured to these panels, and it separates the air conditioning unit housing into two chambers 75 for cold air and 76 for hot air.

35 45 In the chamber 75 the cold air is passing downwardly around the lower end 77 of baffle 74, and in chamber 76 the air is heated and passes upwardly.

40 50 Baffle 74 is provided with a diagonally extending offset 78 located between its upper and lower edges for the purpose of increasing the size of the lower part of the cold air chamber 75 by locating the lowermost portion 79 of the baffle 74 forwardly of the uppermost portion.

55 55 The cold air chamber 75 is also adapted to house a hopper 80 which has its filling opening at 42 (Fig. 1). The upper part of the hopper 80 is closed by a sheet metal member which may have an upwardly and diagonally extending portion 82 and a pair of integral roof portions 83, 84 joined together along a ridge 85, and another diagonally extending portion 86.

60 65 This metal plate, consisting of the parts 82-85, is symmetrical when viewed from the front or rear, and constitutes a baffle 90 for separating the air coming in at the cold air opening 44 into two streams to pass outward through the air filters 87, 88, which are vertically disposed on each side of the baffle 90. The filters 87, 88 may comprise any commercial air filter, but is preferably of the type having a metal frame and a suitable foraminated cover on each side of the frame, the space between the coverings being 70 75 filled with glass wool suitably coated with ad-

hesive compound and adapted to strain out of the air all types of solid foreign materials.

The cold air chamber 75 is provided with suitable vertically extending guide members 91 for slidably receiving the frames of the filters 87, 88 to hold them in vertical position and in spaced relation to the side panels 25, 26 of the air conditioning unit.

The filters may be slid in from the front of the air conditioning unit by removing the front panel 28, and may easily be renewed at any time. At their rear ends the filters 87, 88 and the baffle 90 engage the rear wall 92 of the hopper, which may have a diagonally extending portion 93 and a lower vertically extending portion 94. The space between the baffle 74 and the wall 92 permits a small amount of cold air to pass by the filters 87, 88 without being filtered; but it also serves to cool the hopper on all sides.

In other embodiments of the invention the space between the walls 92 and 74 may be blocked off so as to cause all of the air to pass through the filters and still maintain a dead air space surrounding the hopper.

The hopper 80 may have its front wall 95 formed of a piece of sheet metal of substantially rectangular form, which extends upward and is joined at the top to the baffle member 90. This front wall has the hopper aperture 42, which is closed by the door 41. The rectangular front wall 95 of the hopper is bent backwardly at 96 and has a diagonal downwardly extending portion 97 adapted to guide the fuel in the hopper over into the rectangular feed box 98.

The sides of the hopper may be formed by a pair of panels secured to the plate portions 95, 96, 97, 93, 94 and of a shape shown in Fig. 2 and having a downwardly extending rectangular portion 99 forming the sides of the feed box 98.

The feed box 98 has front and rear trapezoidal walls 100 and 101, which are formed at the lower edge with a half cylindrical groove for receiving the conveyor tube 103, and the feed box 98 may be provided with a pair of bottom sections 104 engaging each side of the conveyor tube 103 and effecting a substantial closure of the bottom of the hopper.

The conveyor tube 103 has its upper portion cut away to form an opening where it engages the bottom of the hopper so that the fuel may flow freely from the hopper into the conveyor tube where it is engaged by a screw conveyor.

The end walls 100 and 101, being trapezoidal and tapering toward their lower edges, causes the side panels 99 of the feed box to slope toward each other to direct the fuel into the conveyor tube 103.

The feed box 98 preferably has an opening in its front wall 101, communicating with a box-like extension 105 fitted on a continuation of the same opening in the conveyor tube 103, and having a closure plate 106 secured by a bolt and thumb screw 107. This closure plate 106 may be removed for inspection of the conveyor screw and to remove obstructions.

The conveyor tube 103 communicates at its rear end with the fire pot 108, which may be of any desired construction, and which is provided with suitable grate formations for supporting the fuel that is forced upwardly at its center and spread out on the top of the fire pot.

The fire pot 108 also communicates below its grate and surrounding its fuel feeding aperture with the air supply tube 109, which is bent backwardly and communicates with the blower hous-

ing 110 located beneath the diagonal wall 97 of the hopper. The air tube 109 is preferably provided with a butterfly damper 111 located intermediate its length in an enlarged portion 112.

5 The space below the hopper wall 97, air conditioning unit end panel 28, and hopper wall 100, which is also bound by vertically extending air baffles 113, 114, is indicated by the numeral 115, and it is utilized for location of the controlling mechanism, motor, and blowers.

Twin air circulating blowers having the housings 110 on each side of the air conditioning unit are preferably employed. These blowers have their intake provided by apertures 116 in the 15 baffles 113, 114. The twin impellers 117 are of the centrifugal type, and they may be driven directly by the motor shaft, or they may be mounted as shown in Fig. 3 on the high speed shaft 118, extending from the speed reduction gearing housing 119.

20 The motor 120 in this embodiment is mounted on the speed reduction gearing, and housing 119, and is provided with the pulley 121 engaged by V-belt 122, which also engages the V-pulley 123 on the shaft 118.

25 The gear housing 119 contains the usual speed reduction gears connecting the shaft 118 with the driving worm screw of the worm conveyor in the conveyor tube 103.

30 The speed of operation of the feed screw is determined by the position of the controlling member 124 (Fig. 7), which is pivotally mounted on the trunnion 125, and which has the usual adjustments, as indicated, for permitting the drive of the screw at a number of different speeds from zero, indicating no drive, to 4. This mechanism may be so adjusted that the controlling system of the air conditioning unit can drive the screw at high feed or low feed, and the rate of speed 35 is determined by the adjustment of the stops on the member 124.

40 The blower housings are completed by means of an inner wall 126 for each housing, the wall having an aperture for passing the shaft 118, and by 45 means of the spirally extending outer wall 127 for each housing. These blowers are adapted to discharge into the space below and surrounding the furnace housing 50, which also includes all of the space below the hopper 80.

50 The upper side walls of the hopper 80 are indicated at 128 on each side (Fig. 3), just inside the side panels 25, 26 of the air conditioning unit. This blocks off access of air from the outside of the filters, except through the channels between 55 the side panels 25, 26, and baffles 113, 114.

55 The shaft 118 also supports another impeller 128 of larger diameter and smaller axial thickness for the purpose of supplying air at a lesser volume, but of greater pressure, for supporting 60 combustion in the fire pot 108. This impeller is housed in a blower housing, one wall of which is formed by the wall 126 of the left blower (Fig. 7) and the other wall of which is formed by a plate 130, having an intake aperture 131 surrounding the shaft 118.

65 This blower also has a spirally extending outer wall 132, which leads to a discharge opening that communicates with the air tube 109 leading to the fire pot 108. The air for this impeller is drawn in from the space 115 surrounding the driving mechanism through the intake aperture 131.

70 In the embodiment of Fig. 8 all of the impellers 117, 117, 128 are mounted on the motor shaft 133, which is provided with pulley 121, belt 122,

driven pulley 123 on the high speed shaft 118 of the gear housing 119.

An axially movable clutch member 134 is splined to the shaft 118 and engageable with the complementary member on the pulley 123, which is mounted for free rotation on shaft 118.

In this embodiment the connecting linkage 135 is adapted to disconnect the drive pulley 123 of the gear housing 119 entirely from the motor 120 so that there would be either a high rate of feed of coal or no feed at all, while the blowers would continue to operate constantly, being directly connected to the shaft of motor 120.

In the embodiment of Fig. 7, it should also be noted that the speed changing arrangements 124, 125 affect the speed of the coal feed screw and cannot affect the driven shaft 118, which carries the impellers of the air blowers, and which is directly driven by a belt from the motor 120. Thus, the blowers operate at all times when the motor is operating, but the coal feed is adapted to be changed from high to low feed or from high feed to no feed, by reason of the regulation of a controlling system further to be described.

The course of the air through the air conditioning unit housing is as follows: Cold air comes in at the opening 44 (Fig. 2) and passes down on both sides of the baffle 90, which forms the roof of the coal hopper. It then passes laterally out through the filters 87, 88 and downward through passages 136, 137 to the circulating blowers, whose intake is located at 116. These blowers impel the air rearwardly in the air conditioning unit housing under and around the furnace housing 50, where the air is heated and is passed upwardly into engagement with the lower faces 63 of the heat box at the top of the furnace until the hot air emerges at the opening 45, where it is conducted into the hot air ducts leading to the rooms. It is returned from the rooms by cold air ducts leading to the opening 44 and constantly circulated, while the motor is running, by the circulating blowers.

A certain amount of the air which is taken in to the space 115 is used by the combustion blower 128 and driven through the air tube 109 into the fire box, where it is used for supporting combustion of the coal. This air is never wholly shut off when the motor is operating, but its flow may be diminished from high feed to low feed by means of the butterfly damper 111, which is also controlled by the control system, further to be described.

This damper closes the air tube 109 partially and greatly reduces the flow of the air for combustion, but provides enough air so that the coal in the fire pot is burned up and the smoke is reduced to a minimum. In fact, so far as I have been able to observe, there is no visible smoke produced by the operation of the present heating unit.

All of the parts of the air conditioning unit are preferably made of steel, welded together or otherwise secured by bolts or screws or other suitable fastening means, such as rivets, the welding being preferred, and the steel is preferably of a type adapted to withstand corrosion, such as copper bearing steel.

The outside of the unit may be provided with any desired decorative finish or coating of paint, and all of the mechanism of the unit, including the controlling devices, may be installed in the main housing so that it is ready to be set in place and merely need be connected to the electrical circuit and the chimney.

Referring now to Fig. 9, this is a wiring diagram of a controlling system adapted to be used for operating the stoker. The system includes a room thermostat 140, consisting of a thermostatic switch located in the rooms to be heated, and having the contacts 141, 142. It also includes a controlling switch assembly, which consists of two thermostatic switches, one called the limit switch, 143, and the other called the operating switch, 144.

The limit switch and the operating switch, in the case of a hot air heater, would be disposed in the plenum chamber, and would consist of thermostatic electric switches; but in the case of a steam boiler, the limit switch and operating switch would consist of pressure actuated electric switches, with the pressure responsive device in the boiler exposed to steam pressure. In either case, the limit switch would be provided with a pair of electric contacts 145, 146, and the operating switch with two pairs of electric contacts 147, 148, and 149, 150.

The contacts of the limit switch would be opened only when the temperature in the plenum chamber reaches or exceeds a predetermined safe value, such as, for example, 350 degrees F., or when the steam pressure arrives at a predetermined value exceeding safety. At all other times the limit switch would have its contacts 145, 146 closed.

The operating switch would be so arranged that an increase of temperature above 150 degrees F. would open contacts 149, 150 and close contacts 147, 148; when the temperature of the plenum chamber decreases below 150 degrees F., the contacts 147, 148 would be opened and the contacts 149, 150 closed.

This is accomplished by means of the movable switch arm 151, which is movable responsive to changes of temperature, by means of a thermostat, or movable responsive to changes in pressure, where the device is used on a steam boiler.

The operating switch may also be disposed in the water of the boiler, and may be movable responsive to the temperature of the water.

The circuit may be energized by means of a 110 volt, 60 cycle lighting circuit, the leads of which are indicated at 152, 153; and the lead 152 may be connected directly to the contact 146.

Contact 145 is connected by a conductor 154 to the movable switch arm 151 of the operating switch, and also by a conductor 155 to a terminal A of the transformer 156. This terminal is that of the high voltage primary 157 of the step-down transformer, the other terminal of which is indicated at B; and terminal B is directly connected to the line conductor 153.

The fixed contact 148 of the operating switch is connected by conductor 158 to a terminal D, and fixed contact 149 is connected by conductor 159 to a terminal C of the controlling mechanism.

The room thermostat 140 has its contact 141 connected by conductor 160 to a terminal R, and by a conductor 161 to a terminal W. The pilot switch 162 has its contacts 163, 164 connected by conductors 165 and 166 to the terminals W and R, respectively. Those circuits connected to the terminals R and W may be controlled either by the pilot switch or the room thermostat, and may be energized by either of these controlling devices.

The pilot switch is an electric switch adapted to be closed periodically, by a pilot clock, indicated at 167, which may comprise an electric motor clock. This clock is energized by con-

ductor 168 from terminal B, which is connected to line at 153, and by conductor 169, which leads to terminal C that is connected by conductor 159 to the operating switch contact 149 for a purpose further to be described.

The terminal W is connected by conductor 170 to one terminal of a relay coil 171, the relay controlling the contacts 172 and 173. The other terminal of the relay coil is connected by conductor 174 to the secondary 175 of the step-down transformer, which has its other terminal connected by conductor 176 to the terminal R. Thus the room thermostat is connected in series with the secondary of the transformer and with the relay coil 171 so that when the room thermostat contacts 141, 142 are closed the relay 171 is energized to close the contacts 172, 173.

The same result may be accomplished by means of the closing of the pilot switch contacts 163, 164. The relay contacts 172, 173 control the energization of the motor 120, which drives the blowers for circulating air, and for the air of combustion, and which also drives the feed screw of the stoker.

The motor 120 has its terminals connected by conductors 177 and 178 to terminals E and F. Terminal E leads back through conductor 179 to terminal A, and through conductor 155 to contact 145. This is ordinarily connected to contact 146, which is connected to conductor 152 of the line. The other lead from the motor 120, which is indicated at 178, is connected through the terminal F and a conductor 180 to relay contact 172. Relay contact 173 is connected by conductor 181 to the terminal B, which is directly connected to the line at 153. Thus the motor is adapted to be controlled by the relay 171 and energized by it whenever the limit switch is closed; but the limit switch is adapted to de-energize the whole system through its direct breaking of the energizing circuit at the contacts 145, 146.

The controlling circuit also includes a pair of solenoids, one of which may be termed the "off and minimum air" solenoid, and the other the "high" solenoid. Each of these solenoids includes a coil, indicated at 182, for the "off and minimum air" solenoid; and 183 for the "high" solenoid. The "high" solenoid has its coil connected by conductor 184 to the terminal C. This terminal is connected by conductor 159 to contact 149. The contacts 149, 150 may be called the hot contacts of the operating switch because they are opened when the operating switch reaches the hottest operating temperature for the plenum chamber.

The contacts 147, 148 may be called the cold contacts because they are closed when the plenum chamber is hot enough, and the next cycle permits the cooling of the plenum chamber until it reaches a predetermined lower temperature.

The other terminal of the solenoid coil 183 is connected to a contact 185, which is adapted to be engaged by the contact 186 of a movable switch arm 187. This movable switch arm has another contact 188 at its opposite end, adapted to engage the contact 189, which is connected to one terminal of the "off and minimum air" solenoid 182. The other terminal of this solenoid is connected by conductor 190 to the terminal D, which leads back through conductor 158 to contact 148.

The switch arm 187 is connected by conductor 191 to the terminal F of the motor circuit. Thus both of these solenoids are adapted to be con-

trolled by the relay 171, through its contacts 172, 173, and also by the operating switch 144 through its contacts 148 and 149.

The operation of the foregoing system is as follows: When the temperature of the plenum chamber does not exceed a safe temperature of say, for example, 350 degrees F., the limit switch contacts 145, 146 will be closed, and the step-down transformer 156 will have its primary energized through the following circuit: line conductor 153, primary 157, conductor 155, contacts 145, 146, conductor 152.

Suppose, for example, under these conditions the temperature of the room, in which the room thermostat is located, decreased below the thermostat setting. The room thermostat contacts 141, 142 would close, and this would close the circuit through the secondary 175 of the transformer 156, as follows: contacts 141, 142, conductor 161, relay 171, conductor 174, secondary 175, conductor 176, conductor 160, to contact 141.

The closure of the secondary circuit energizes the relay coil 171, closing the relay contacts 172, 173. This completes the motor circuit through the following conductors: contact 172, conductor 180, conductor 178, motor 120, conductor 177, conductor 179, conductor 155, contacts 145, 146, conductor 152, to the line conductor 153, conductor 181, contact 173.

The motor then drives the air circulating blowers and the air combustion blower and the gears which actuate the feed screw for the stoker. The fuel bed is supplied with additional coal and a blast of air for combustion.

If at this time the temperature of the heating plant, that is, the plenum chamber, is below 150 degrees F., or if the steam pressure is below a predetermined value, the contacts 149, 150 are closed.

Assuming the contacts 185, 186 of the high solenoid are closed, this would energize the high solenoid 183 through the following circuit: contacts 185, 186, switch arm 187, conductor 191, conductor 180, contacts 172, 173, conductor 181, conductor 153, to line conductor 153, contacts 145, 146, conductor 154, switch arm 151, conductors 149, 150, conductor 159, conductor 184, solenoid 183, contact 185.

The energization of the high solenoid 183 will cause its core to be drawn into the solenoid, and the core has an insulating extension 195, which engages the switch arm 187 and opens the contacts 185, 186, closing the contacts 188, 189. The high solenoid plunger 183 is adapted to actuate the member 124 on the gear case 119 and put the coal feed on high. It also actuates the stoker air shutter 111 to the high or open position; but it leaves these devices under the control of the solenoid 182 because of the closure of the contacts 188, 189.

The solenoid 183 is removed from its controlling position by the opening of contacts 185, 186. The stoker will then be fired on high, that is, with the maximum feed of coal and air, and the firing at this rate will continue until change of temperature conditions is brought about in the room or in the plenum chamber acting on the operating switch.

Suppose, for example, the thermostat called for heat and the heating plant, that is, the plenum chamber, has its temperature already above 150 degrees F. The contacts 149, 150 would then be opened, and the contacts 147, 148 would be closed.

In this case current would flow through the

circuits by virtue of the closure of the contacts 172, 173 of the relay to energize the "off and minimum air" solenoid 182 through its contacts 188, 189.

It should be understood that the question whether the air or coal feed is merely reduced or turned completely off depends upon the adjustment of the stops on the gear box 119.

The core of this solenoid would be pulled up, changing the coal feed from high to off, and cutting the air supply to a minimum by closing the shutter 111, although the blower for combustion air would still be operating whenever the motor 120 is energized.

At the end of its inward stroke, the plunger of solenoid 182 would break the contacts 188, 189 and close the contacts 185, 186 by means of an insulating plunger extension 196. Under these conditions, with the temperature of the plenum chamber already above 150 degrees F., the fire bed would be supplied with a minimum amount of air for combustion and fed with coal at a low rate of feed.

The air condition circulating blower would deliver warm air to the space to be heated, until the room thermostat is satisfied, unless the fire gets too low to maintain the 150 degrees F. temperature. If the fire bed should get that low, then the contacts 147, 148 would open, and contacts 149, 150 would close, cutting the stoker on high coal feed and high air feed.

Under all of these conditions, the limit switch would still be in full control of the system, and it would not allow the stoker to operate at all if the heating plant temperature were higher than a safe temperature setting, such as, for example, 350 degrees F.

The contacts 163 and 164 of the pilot coil switch are for pilot or kindling operations to maintain a small fire between the periods of the operation of the stoker responsive to thermostat heat demands.

When the limit switch contacts are open, it should be noted that even the pilot switch is not energized, and the pilot cannot start the stoker under these conditions. This is of great advantage because it tends to keep down the temperature over-run of the furnace.

It should also be noted that if the limit switch contacts are closed the pilot switch may operate; but if the contacts 149, 150 are open, the pilot operation will be with the coal feed off and the air at a minimum. This will eliminate temperature over-run of the furnace. In other words, the operation of the pilot switch for kindling operations is carried on at a minimum air feed, with coal feed off, if the temperature of the plenum chamber is above the predetermined value set by the operating switch.

If, however, the position of the operating switch shows that the plenum chamber temperature is low, then kindling operations will be carried on at high fire combustion, with high feed of coal and air.

The present controlling arrangements are adapted to be used not only for the present air conditioning and heating unit, but for stokers which are installed in old furnaces. In such case the coal feed would not be completely cut off, but would be merely reduced from high to low, such as from a No. 4 feed on high, to a No. 1 feed on low, as exemplified by the mechanism of Fig. 7. In the installations having the present air conditioning and heating unit, the coal feed is preferably completely cut off, when

the air feed is cut to a minimum, as exemplified by the use of a clutch in Fig. 8.

It will thus be observed that I have invented an improved air conditioning and heating unit, in which a single motor is adapted to drive the air circulating blowers and the blower for combustion air.

This unit contains all of the structure necessary for the circulation of the air, filtering and heating and its controlling apparatus, and may be shipped from the factory and installed as a unit. Its hopper is enclosed in the housing. The arrangement is such that all of the elements necessary for the operation of the stoker and circulation of the air are enclosed in one unitary housing.

The efficiency of the present air conditioning and heating unit is higher than that attained by any of the devices of the prior art for the reason that more perfect combustion is secured and the coal bed is kept at a minimum depth. Temperature over-run of the furnace is eliminated or minimized by cutting the feed of the coal from high to zero or low and reducing the air blast from high to low after a predetermined period of operation on high coal feed.

I have found that installations embodying the present system will maintain the room temperature of a stoker fired system so uniform that it does not vary one-half degree F. during a twenty-four hour period of operation, while the outside temperature drops from 44 degrees F. to 12 degrees F. below zero. The same room thermostat which, with the devices of the prior art, could not hold the room or laboratory within five degrees F. of the setting of the room thermostat, was adapted, with the present system, to maintain the temperature substantially constant, with no variation of more than one-half degree F.

Temperature over-runs were eliminated because the green coal forced in on high firing is substantially all burned up just before the thermostat is satisfied on the low firing.

I desire it to be understood that the temperatures which are used as examples in this description are not limitative in any sense, and the present devices may be arranged to operate at any temperatures suitable for stoker fired heating plants.

The present air conditioning unit may also be used with a bin feed stoker, in which case the coal will be fed to the burner from a bin instead of from the hopper, as shown, involving the use of a longer screw and screw housing, but the other structure of the unit may be substantially the same.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. In an air conditioning and heating system, the combination of a furnace unit housing provided with a furnace at one end and provided with an inlet at its opposite end, blower means for receiving the air from said inlet and directing it towards said furnace, said housing being provided with a hot air outlet, an electric motor for driving said blower means, combustion air blower means driven by the same electric motor and

having an air pipe extending to said furnace, speed reduction drive means driven by said motor, coal feeding means driven by said drive means for supplying fuel to said furnace, thermostatic controlling means controlled by the temperature of the air in the plenum chamber for controlling said fuel feeding means, and an air damper in said air pipe from said combustion air blower for diminishing the flow of combustion air when the rate of coal feed is cut down, the circulating blowers and combustion air blower operating at all times when the electric motor is driven.

2. In an air conditioning and heating system, the combination of a furnace unit housing provided with a furnace at one end and provided with an inlet at its opposite end, blower means for receiving the air from said inlet and directing it toward said furnace, said housing being provided with a hot air outlet, an electric motor for driving said blower means, combustion air blower means driven by the same electric motor and having an air pipe extending to said furnace, speed reduction drive means driven by said motor, coal feeding means driven by said drive means for supplying fuel to said furnace, thermostatic controlling means controlled by the temperature of the air in the plenum chamber for controlling said fuel feeding means, and an air damper in said air pipe from said combustion air blower for diminishing the flow of combustion air when the rate of coal feed is cut down, the circulating blowers and combustion air blower operating at all times when the electric motor is driven, said thermostatic means comprising an operating switch in the plenum chamber, having alternate pairs of contacts to be broken or engage alternately, depending upon the temperature, whereby the coal feed is cut to a low rate as soon as the temperature in the plenum chamber reaches a predetermined value.

3. In an air conditioning and heating system, the combination of a furnace unit housing provided with a furnace at one end and provided with an inlet at its opposite end, blower means for receiving the air from said inlet and directing it toward said furnace, said housing being provided with a hot air outlet, an electric motor for driving said blower means, combustion air blower means driven by the same electric motor and having an air pipe extending to said furnace, speed reduction drive means driven by said motor, coal feeding means driven by said drive means for supplying fuel to said furnace, thermostatic controlling means controlled by the temperature of the air in the plenum chamber for controlling said fuel feeding means, and an air damper in said air pipe from said combustion air blower for diminishing the flow of combustion air when the rate of coal feed is cut down, the circulating blowers and combustion air blower operating at all times when the electric motor is driven, said thermostatic means comprising an operating switch in the plenum chamber, having alternate pairs of contacts to be broken or engage alternately, depending upon the temperature, whereby the coal feed is cut to a low rate as soon as the temperature in the plenum chamber reaches a predetermined value, and a room thermostat for controlling the energization of said motor, said room thermostat operating said motor until the demand for heat is supplied in the room.

4. A control system for stokers comprising a coal feeding means for supplying fuel to a fur-

nace, an electric driving motor, combustion air blower means driven by said electric motor and having an air pipe extending to said furnace, speed reduction drive means driven by said motor and actuating said coal feeding means, said speed reduction drive means being variable for high or low feed of coal, means for controlling the flow of combustion air in said air pipe, and controlling means controlled by the condition 10 of the furnace in respect to heat generation for transmission to the space to be heated for controlling the positions of said speed reduction drive means and said means for controlling flow of combustion air.

15 5. A control system for stokers comprising a double-throw thermostatic electric switch having high temperature and low temperature contacts, coal feeding means and combustion air feeding means, an electric motor for driving said coal feeding and air feeding means, operative 20 mechanical connections between said motor and said coal feeding means and said air feeding means, and electrical means controlled by said double-throw thermostatic switch responsive to the temperature condition of air in the plenum 25 chamber of the furnace for controlling the rate of supply of air and coal by said feeding means, whereby the fire is supplied with air and coal as required to maintain the furnace within predetermined temperature limits.

30 6. A control system for stokers comprising a double-throw thermostatic electric switch having high temperature and low temperature contacts, coal feeding means and combustion air feeding means, an electric motor for driving said coal feeding and air feeding means, operative 35 mechanical connections between said motor and said coal feeding means and said air feeding means, and electrical means controlled by said double-throw thermostatic switch responsive to the temperature condition of air in the plenum chamber of the furnace for controlling the rate of supply of air and coal by said feeding means, whereby the fire is supplied with air and coal as required to maintain the furnace within predetermined temperature limits, said air feeding means being operated continuously for the purpose of removing smoke at all times and burning up the excess coal forced into the fire pot 40 during operation of the coal feeding means.

45 7. A control system for stokers comprising a double-throw thermostatic electric switch having high temperature and low temperature contacts, coal feeding means and combustion air feeding means, an electric motor for driving said coal feeding and air feeding means, operative 50 mechanical connections between said motor and said coal feeding means and said air feeding means, electrical means controlled by said double-throw thermostatic switch responsive to the temperature condition of air in the plenum chamber of the furnace for controlling the rate of supply of air and coal by said feeding means, whereby the fire is supplied with air and coal as required to maintain the furnace within predetermined temperature limits, a circulation air blower driven by the same electric motor, and a room thermostatic switch for controlling the operation of said motor separately from said double-throw thermostatic switch and adapted to energize the motor when there is a demand for heat in the room.

55 8. A control system for stokers comprising a double-throw thermostatic electric switch having high temperature and low temperature con-

tacts, coal feeding means and combustion air feeding means, an electrical motor for driving said coal feeding and air feeding means, operative mechanical connections between said motor and said coal feeding means and said air feeding means, electrical means controlled by said double-throw thermostatic switch responsive to the temperature condition of air in the plenum chamber of the furnace for controlling the rate of supply of air and coal by the said feeding means, whereby the fire is supplied with air and coal as required to maintain the furnace within predetermined temperature limits, a circulation air blower driven by the same electric motor, a room thermostatic switch for controlling the operation of said motor separately from said double-throw thermostatic switch and adapted to energize the motor when there is a demand for heat in the room, and a safety limit switch comprising a thermostatic switch adapted to be opened at a predetermined high limiting temperature of the furnace, controlling the energization of all the circuits of said system.

9. A control system for stokers comprising a double-throw thermostatic electric switch having high temperature and low temperature contacts, coal feeding means and combustion air feeding means, an electric motor for driving said coal feeding and air feeding means, operative mechanical connections between said motor and said coal feeding means and said air feeding means, electrical means controlled by said double-throw thermostatic switch responsive to the temperature condition of air in the plenum chamber of the furnace for controlling the rate of supply of air and coal by said feeding means, whereby the fire is supplied with air and coal as required to maintain the furnace within predetermined temperature limits, and a periodically actuated time controlled pilot switch separately controlling the energization of said motor for turning on the motor and feeding coal and air to the furnace periodically to maintain the fire.

10. A control system for stokers comprising a double-throw thermostatic electric switch having high temperature and low temperature contacts, coal feeding means and combustion air feeding means, an electric motor for driving said coal feeding and air feeding means, operative mechanical connections between said motor and said coal feeding means and said air feeding means, electrical means controlled by said double-throw thermostatic switch responsive to the temperature condition of air in the plenum chamber of the furnace for controlling the rate of supply of air and coal by said feeding means, whereby the fire is supplied with air and coal as required to maintain the furnace within predetermined temperature limits, and a periodically actuated time controlled pilot switch separately controlling the energization of said motor for turning on the motor and feeding coal and air to the furnace periodically to maintain the fire, said system being arranged to feed the fire pursuant to energization by the pilot switch on high or low feed, depending on the temperature of air in the plenum chamber responsive to said double-throw thermostatic switch.

11. A stoker controlled system comprising a heater having a fire pot, coal feeding means for feeding coal to said fire pot, a combustion air blower for supplying air to said heater, an electric motor for driving said blower and coal feeding means, a selective drive interposed between

5 said coal feeding means and said motor, having two rates of drive, one for low coal feed, and one for high coal feed, electric control means for said motor located at the heater and adapted to be actuated responsive to the condition of the heater in respect to the generation of a predetermined supply of heat at the heater, coal feed control means arranged and constructed to move said selective drive to high or low coal feed, depending upon said controlling means, said controlling means effecting a low coal feed when the heater reaches a predetermined high temperature, and a high coal feed when said heater reaches a predetermined low temperature, controlling means located in a room to be heated, generated at said heater, for controlling the supply of heat to said room responsive to the demand for heat in the room, a time controlled switch means for controlling the energization of said motor and effecting a coal feed at predetermined periods of time to act as a pilot and maintain combustion, and limit switch means controlling all of the electric circuits of said system and adapted to de-energize the system 20 upon the reaching of a predetermined higher temperature at said heater.

12. A stoker controlled system comprising a fire pot, a coal feeding means for feeding coal to said fire pot, selective drive means for actuating said coal feeding means at one of two rates of feed, comprising high coal feed and low coal feed, an electric motor, operative connections between said electric motor and said selective drive, a combustion air blower driven by said motor, an air circulation blower driven by said motor, a motor controlled relay for controlling the energization of said motor, a high voltage electric circuit for energization of said motor, a transformer energized from said high voltage circuit and adapted to provide low voltage for energizing said relay, an operating switch for controlling the energization of said relay and through it of the motor, said operating switch comprising a thermostatically actuated switch located in the plenum chamber of a furnace housing surrounding said fire pot, electrically controlled means for controlling the selection of high or low coal feed by said selective drive, said electrically controlled means being controlled by said operating switch to provide a low coal feed when the temperature of the plenum chamber reaches a predetermined high value and high coal feed when the temperature of the plenum chamber reaches a predetermined low value.

13. A stoker controlled system comprising a fire pot, a coal feeding means for feeding coal to said fire pot, selective drive means for actuating said coal feeding means at one of two rates of feed, comprising high coal feed and low coal feed, an electric motor, operative connections between said electric motor and said selective drive, a combustion air blower driven by said motor, an air circulation blower driven by said motor, a motor controlled relay for controlling the energization of said motor, a high voltage electric circuit for energization of said motor, a transformer energized from said high voltage circuit and adapted to provide low voltage for energizing said relay, an operating switch for controlling the energization of said relay and through it of the motor, said operating switch comprising a thermostatically actuated switch located in the plenum chamber of a furnace

housing surrounding said fire pot, electrically controlled means for controlling the selection of high or low coal feed by said selective drive, said electrically controlled means being controlled by said operating switch to provide a low coal feed when the temperature of the plenum chamber reaches a predetermined high value and high coal feed when the temperature of the plenum chamber reaches a predetermined low value, and a thermostatic limit switch for controlling the energization of all of the circuits of said system whereby the system is de-energized when the temperature in the plenum chamber reaches a predetermined upper value.

14. A stoker controlled system comprising a fire pot, a coal feeding means for feeding coal to said fire pot, selective drive means for actuating said coal feeding means at one of two rates of feed, comprising high coal feed and low coal feed, an electric motor, operative connections between said electric motor and said selective drive, a combustion air blower driven by said motor, an air circulation blower driven by said motor, a motor controlled relay for controlling the energization of said motor, a high voltage electric circuit for energization of said motor, a transformer energized from said high voltage circuit and adapted to provide low voltage for energizing said relay, an operating switch for controlling the energization of said relay and through it of the motor, said operating switch comprising a thermostatically actuated switch located in the plenum chamber of a furnace housing surrounding said fire pot, electrically controlled means for controlling the selection of high or low coal feed by said selective drive, said electrically controlled means being controlled by said operating switch to provide a low coal feed when the temperature of the plenum chamber reaches a predetermined high value and high coal feed when the temperature of the plenum chamber reaches a predetermined low value, and air valve means for controlling the inlet of air to said combustion blower, said air valve means being partially closed when the coal feed is on low feed and opened to a predetermined amount when the coal feed is on high feed, by means of an operative mechanical connection between said valve and said controlling means.

15. A stoker controlled system comprising a fire pot, a coal feeding means for feeding coal to said fire pot, selective drive means for actuating said coal feeding means at one of two rates of feed, comprising high coal feed and low coal feed, an electric motor, operative connections between said electric motor and said selective drive, a combustion air blower driven by said motor, an air circulation blower driven by said motor, a motor controlled relay for controlling the energization of said motor, a high voltage electric circuit for energization of said motor, a transformer energized from said high voltage circuit

- and adapted to provide low voltage for energizing said relay, an operating switch for controlling the energization of said relay and through it of the motor, said operating switch comprising a thermostatically actuated switch located in the plenum chamber of a furnace housing surrounding said fire pot, electrically controlled means for controlling the selection of high or low coal feed by said selective drive, said electrically controlled means being controlled by said operating switch to provide a low coal feed when the temperature of the plenum chamber reaches a predetermined high value and high coal feed when the temperature of the plenum chamber reaches a predetermined low value, and air valve means for controlling the inlet of air to said combustion blower, said air valve means being partially closed when the coal feed is on low feed and opened to a predetermined amount when the coal feed is on high feed, by means of an operative mechanical connection between said valve and said controlling means, and means for maintaining combustion at a rate dependent upon the position of the operating switch for energizing said relay at predetermined time intervals to drive the motor and maintain combustion.
16. A stoker controlled system comprising a fire pot, a coal feeding means for feeding coal to said fire pot, selective drive means for actuating said coal feeding means at one of two rates of feed, comprising high coal feed and low coal feed, an electric motor, operative connections between said electric motor and said selective drive, a combustion air blower driven by said motor, an air circulation blower driven by said motor, a motor controlled relay for controlling the energization of said motor, a high voltage electric circuit for energization of said motor, a transformer energized from said high voltage circuit and adapted to provide low voltage for energizing said relay, an operating switch for controlling the energization of said relay and through it of the motor, said operating switch comprising a thermostatically actuated switch located in the plenum chamber of a furnace housing surrounding said fire pot, electrically controlled means for controlling the selection of high or low coal feed by said selective drive, said electrically controlled means being controlled by said operating switch to provide a low coal feed when the temperature of the plenum chamber reaches a predetermined high value and high coal feed when the temperature of the plenum chamber reaches a predetermined low value, and a room thermostat connected to control said relay and adapted to effect an energization of said motor, and a feed of coal when there is a demand for heat in the room, the rate of coal feed being dependent upon the temperature in the plenum chamber and being controlled by said operating switch.

WILLIAM W. HALLINAN.
